Primary Examiner — R. Johnson(74) *Attorney, Agent, or Firm* — Calfee, Halter & Griswold LLP(57) **CLAIM**

The ornamental design for a seat as shown and described.

DESCRIPTION

FIG. 1 is a perspective view of a seat of the new design in a first position;

FIG. 2 is a front elevational view of the seat of FIG. 1;

FIG. 3 is a rear elevational view of the seat of FIG. 1;

FIG. 4 is a left side elevational view of the seat of FIG. 1, the right side elevational view being a mirror image thereof;

FIG. 5 is a top plan view of the seat of FIG. 1;

FIG. 6 is a bottom plan view of the seat of FIG. 1;

FIG. 7 is a perspective view of the seat of the new design in a second position;

FIG. 8 is a front elevational view of the seat of FIG. 7;

FIG. 9 is a rear elevational view of the seat of FIG. 7;

FIG. 10 is a left side elevational view of the seat of FIG. 7, the right side elevational view being a mirror image thereof; and,

FIG. 11 is a top plan view of the seat of FIG. 7.

The broken lines are included for the purpose of illustrating portions of the article and form no part of the claimed design.
